UNITED STATES PATENT OFFICE.

ROBERT C. GROH, OF ST. PAUL, MINNESOTA, ASSIGNOR, BY DIRECT AND MESNE ASSIGNMENTS, TO W. H. DEUBENER, OF ST. PAUL, MINNESOTA.

CARRYALL BAG.

Application filed January 16, 1922. Serial No. 529,693.

To all whom it may concern:

Be it known that I, ROBERT C. GROH, a citizen of the United States, residing at St. Paul, in the county of Ramsey and State of Minnesota, have invented new and useful Improvements in a Carryall Bag, of which the following is a specification.

My invention relates to bags of the type commonly used for carrying small parcels and the like, its object being to provide improved cord means arranged in connection with bags, as the ordinary paper bag, to support the same and form handles.

A particular object of my invention is to provide cord supporting means that will reinforce and brace the bottom of the bag where the greatest strain occurs, without cutting and damaging the bag, and which is possessed of other advantages which will be hereinafter more specifically set forth and claimed. To this end, my invention consists in the construction, combination, and arrangement of parts hereinafter more particularly described.

In the accompanying drawings, forming part of this specification:

Figure 1, is a perspective view of a bag embodying my features of invention.

Figure 2, is a sectional view on line x—x of Figure 1; and

Figure 3, is a bottom view of a bag embodying my features of invention.

Referring to the drawings, A represents an ordinary paper bag. In carrying out my invention, I employ a pair of cords 2 and 3, each of said cords being made endless for the purpose hereinafter set forth, by means of the knots 4 and 5.

The cords 2 and 3, before being made endless by the knots 4 and 5, are threaded inwardly through the openings 6 in the top of the sides of the bag, and outwardly through the openings 7 in the lower portion of the sides of the bag, and thence threaded through the openings 8 in the sides of the bottom of the bag, one carrier cord being threaded under and over the other carrier cord upon the bottom of the bag; these interlaced portions 13 of the cords being positioned at the center of the bottom of the bag, as shown in Figure 3, with the cords diagonally radiating to the openings 8 in the corners of the bag bottom. The openings 6 and 8 are preferably protected by eyelets 12. The cords 2 and 3, as shown,

project above the bag to constitute handles 10.

I am aware that it is old to support bags by different cord arrangements, as where an endless cord is threaded through openings in the sides of the bag and pass in parallel position around the bottom of the bag, and wherein cords are permanently attached to the top of the bag, etc., and my construction has been designed to obviate the well known objections to these forms.

It is desirable to have the cords support the bottom of the bag, so that the paper bottom of the bag will not have to carry the load and be broken by the variety of objects carried in a bag of this kind in shopping use. Where a single endless cord is employed, which passes around the bag in parallel position, the weight of objects within the bag pressing down upon the bag bottom, particularly in the center of the bag bottom, has a tendency to break the bottom of the bag. There is also the tendency of the endless cord to cut through the bottom of the bag in the sliding movement of the cord.

In my construction, the central interlacing of the independent cords 2 and 3 underneath the bottom of the bag, prevents freedom of sliding, and I have found in use that the interlaced portions 13 will remain at the center of the bottom of the bag when either handle is pulled upon. At the same time, the sliding movement of the cord through the openings 6 and 7 will accommodate the cords to the folding of the bottom of the bag against the sides of the bag, as in packing the bags, and in holding the bottom of the bag in its normal folded position when the bag is not in use. When the bottom of the bag is folded against the sides, the crossed over portions 13 will remain at the center of the bottom of the bag, as shown in Figure 3, with one of the endless cords sliding downwardly through the openings 6 and 7 to permit the opposite folding of the bottom, permitting the other cord to be slid upwardly through the openings 6 and 7 to assist in holding the bottom of the bag against the side of the bag and prevent doubling of the cord under the folded bottom.

I thus secure with my construction the amount of sliding necessary to adapt the construction to a paper bag of this kind, and at the same time obviate a sliding movement across the bottom of the bag to injure and

tear the bag, and also secure a reinforced crossed over support under the bottom of the bag, giving the maximum support at the center of the bag bottom, where there is the greatest weight and strain brought about by the contents of the bag.

I claim:

1. In combination with a paper bag, a pair of independent endless cords one on each side of the bag threaded through openings in the side walls of the bag and projecting above the bag to form handles, said endless cords extending over the bottom of the bag from opposite sides thereof and being interlaced centrally of the bottom of the bag, for the purpose set forth.
2. In combination with a bag of the class described, a pair of endless cords one on each side of the bag threaded through openings in

opposite sides of the bag and through opposed openings in the bag bottom, said cords projecting above the bag to form handles, and being interlaced under the center of the bottom of the bag, for the purpose set forth.

3. In combination with a bag of the class described, formed with a foldable bottom, a pair of endless cords one on each side of the bag threaded through openings in the opposite side walls of the bag and through openings in the sides of the bottom of the bag, said cords being interlaced with each other centrally under the bottom of the bag and extending diagonally from said interlaced portions to the openings in the sides of the bag bottom, said endless cords at the top of the bag constituting handles.

ROBERT C. GROH.
